INJECTOR AND PUMP

Frank Kovach, Lincoln, Nebr.

Application December 20, 1946, Serial No. 717,421

10 Claims. (Cl. 299—107.2)

1

This invention relates to pumps and has for its principal object the provision of a simple and efficient pump which may be operated by the pressure in an engine to discharge fuel, water or other liquid into the engine.

A second object is to provide a fuel injector having a minimum number of parts.

A still further but important object of the invention is to provide a pump or fuel injector particularly suited for use for discharging a fairly viscous inexpensive fuel oil into a relatively slow speed engine such as used for farm tractor engine, and having means whereby the discharge of fuel may be controlled by limiting the travel of the plunger or other discharge member.

The present invention is suited for any type of internal combustion engine but preferably is to be used with an engine utilizing a fuel similar to diesel oil and having some means for igniting the fuel separate from the diesel effect of igniting by the heat generated in compression.

My injector provides a high efficiency, particularly where the fuel is admitted into the injector at a relatively low pressure.

In the drawings:

Figure 1 is a vertical section through the preferred form of my device.

Figure 2 is a modified form.

In Figure 1 the engine cylinder is 10 and its piston is 11. The injector body 12 is threaded to the cylinder as at 14 and preferably has a conical discharge mouth 15. The fuel inlet pipe 16 discharges through an inlet opening 17 to a central bore 18. The lower portion of the injector body has a fairly large chamber 20, and in this chamber a piston 21 travels, being exposed at its bottom to the pressure in the cylinder 10 but constantly urged in a contrary direction by the spring 25. A central sleeve 26 forms a stop to limit the upward travel of the piston 21 at full power output but an adjustable screw 27 having a knurled head 28, can be moved to limit further the upward travel of the piston when so desired, and consequently to lessen the quantity of fluid delivered to the engine.

Integral with the piston 21 is a hollow plunger 30 having a central bore 31 completely through the plunger and piston. The top 32 of the plunger 30 closes the inlet port 17 and forms a cut-off. A spring-pressed one-way valve 34 is mounted near the top of the plunger and a similar valve 36 is located near the bottom of the plunger just above the discharge orifice 37.

As the piston 11 rises in the cylinder 10, the pressure passes through the narrow passage 38 and acts on the bottom of the piston 21 compress-

2

ing the spring 25, and unless the adjustable stop has been lowered, drives the piston against the sleeve 26. This action has cut off the fuel line at 17 and compresses the fuel in the upper portion 5 of the bore 18. The check valve 34 opens and the central bore 31 of the plunger is therefore filled with the fuel which has been trapped from the major supply. The spring 25, as the piston 11 descends, presses the piston 21 down to its bottom stop 39 uncovering the inlet port 17 and again filling the upper portion of bore 18 with fuel. On the next compression stroke the trapped fuel within the bore 31 is discharged into the cylinder as the piston 21 rises. As the piston 21 thus 10 moves the spring closed valves 34 and 36 successively open and the trapped fuel is discharged through the injector opening 37 as a spray. At the top of the strokes of the pistons 11 and 21, the valve 36 closes sharply under the urge of its 15 spring while the parts are momentarily still and this gives what might be called a "sneezing" action, the air expelled from the pressure chamber 20 of the injector body forming a conical stream directed across the discharge orifice 37 and obviating any dripping of fuel.

In the modified form shown in Figure 2, the pressure in the engine cylinder is applied at the top of the injector body and this modification merely illustrates one of the great number of different ways in which the invention can be carried 30 out. In this Figure 2, the cylinder is 40, the engine piston 41, the spark plug 42, and the fuel inlet pipe is 43. The port 44 is closed by a downward movement of the lower end 45 of the plunger 46 which in this case is spring-pressed upwardly 35 by the spring 47. The stop is 48 and the piston of the preferred form is here replaced by a diaphragm 50 against which the plunger 46 is held by its spring 47 positioned by a spring seat on head 53 on the plunger. A pipe 55 leads from the engine cylinder 40 through a hole 56 in the top of the injector body 57 and thus causes the diaphragm 40 to bend downwardly at the center as the engine piston 41 rises in its cylinder 40.

Since plunger 46 in this modified form moves 45 downwardly and cuts off the fuel as it passes the fuel intake port 44, the two cut-off valves 60 and 61 corresponding in purpose to the valves 34 and 36 are in a small member 62 secured in any desired manner to the lower portion of the body of the injector. The fuel discharge orifice 63 sprays the fuel into the engine cylinder as the plunger 46 moves downwardly after closing the intake port 44. In this case the reduction of pressure in the upper chamber of the injector body 55 does not pass air around the injector discharge

port but the spring 47 does create a vacuum in the bore of the member 62 and this effectively prevents undue discharge of fuel as the engine piston 41 moves downwardly subsequent to the firing of the charge by the plug 42.

While I have described the invention in its preferred form as discharging fuel into the cylinder it is obvious that my pump can be used equally well in discharging water or any other fluid into the engine cylinder.

Having described my invention, what I claim is:

1. In a fuel injector for internal combustion engines, a body having therein a central bore, a fuel inlet leading to said bore near the upper end thereof, a pressure chamber, and a cylindrical passageway of less diameter than the pressure chamber, communicating with the chamber and having a conical discharge portion at its free lower end; a piston in the chamber movable in one direction by pneumatic pressure acting through said passageway, spring means for moving the piston in the opposite direction, a hollow plunger in said bore movable with said piston and having its upper end moving in a path to pass said inlet and its lower end moving in the passageway to provide an annular air passage between the plunger and the passageway and to discharge fuel from the hollow of the plunger adjacent said conical portion, a one-way valve in the plunger adjacent the upper inlet end and a second one-way valve in the plunger adjacent the lower end, whereby as the spring means moves the piston, the air below the piston will cross the path of the fuel and thus avoid dripping.

2. A fuel injector for a slow speed engine of the farm tractor type using a fairly viscous fuel at low pressure, including: an injector body having an intermediate bore, a large bore and a smaller bore communicating therewith, a piston mounted in said larger bore with its lower surface constantly open to a variable pressure, a spring urging the piston against said pressure, a plunger slideable in said smaller bore and movable with said piston, a fuel supply line having a port opening into the smaller bore near the closed end thereof, an extension of the plunger having a fuel discharging nozzle and projecting into the intermediate bore so as to leave an annular space, a one-way valve located near the upward end of the plunger, a one-way valve near the discharge end of the nozzle, said plunger moving at all times in accordance with said pressure and moving to cut off said port as the pressure rises, said piston discharging air thru said annular space around the injector nozzle as the injector piston lowers under spring pressure as the pressure lowers.

3. A fuel injector for a slow speed engine using a fairly viscous fuel under low pressure, adapted for mounting in the cylinder block of the engine above the engine piston, including a body having a relatively large diameter chamber, a bore communicating therewith and a passageway establishing free and unrestricted admittance of pressure to the chamber, a pressure responsive member within the chamber, a fuel line having a port opening into said bore, a plunger sliding in the bore and moved by said member to position to cut off the fuel port orifice upon high pressure, spring means to move the plunger to fuel port opening position when the pressure is lowered, an injector nozzle at the bottom of said body, and a pair of coaxial one-way valves located in a passageway forming a fuel space in said body between the fuel entrance orifice and the injector

nozzle, spaced one at each of the two ends of said fuel space and each one-way valve being spring-pressed to prevent pressure passing from the injector nozzle thru the fuel space to the bore and yielding to permit flow of fuel from the bore to the injector nozzle when the fuel port orifice is closed by the plunger, which compresses the fuel trapped in the bore, whereby said fuel space between the two one-way valves is filled with fuel 10 at all times.

4. An injector comprising a two-piece body the lower portion of which includes a bore of relatively large diameter providing a piston chamber and a smaller diameter communicating bore to admit air into the lower portion of said chamber, an upper portion of said body having therein a blind bore of relatively small size, a fuel inlet port leading to said blind bore, a hollow cylinder plunger within the blind bore having an upper end serving as a cut-off for the fuel inlet port and having a lower portion extending into the intermediate bore and out of contact therewith to provide an injector nozzle, a pressure operated piston flange on said plunger engaging the wall 20 of the piston chamber, resilient means urging the piston and the plunger towards discharge position, and one-way spring pressed valves at opposite ends of the plunger.

5. An injector comprising a lower body of two diameters, the smaller diameter portion having a conical nozzle, said body having a major bore and a pressure admitting intermediate bore communicating therewith, the latter having a conically restricted margin form a discharge jet through 30 the nozzle, an upper body having a small blind bore therein and having a fuel inlet port leading to said small bore, a hollow piston in the larger bore having a smaller cylindrical extension on each side, the upper extension fitting 35 the smaller bore and serving as a cut-off for said fuel inlet port and the lower extension having a conical fuel discharge nozzle leaving an annular space between the lower extension and the inside 40 wall of the nozzle, resilient means for moving the piston downward and spaced valve means within 45 said extensions for discharging fuel as the piston moves upwardly, downward movement of piston forcing a gaseous stream thru the annular passageway and across the path of the injected fuel.

6. The device of claim 3 in which the plunger and the member are integral with an axial bore extending through the plunger and through the member and terminating with a restricted conical discharge portion at the bottom, and the valves are located proximate the top and the bottom of the plunger.

7. The device of claim 3 in which a sleeve extends downwardly into the large diameter chamber to form a stop for the member, and an adjustable stop projects into the path of the member to further limit the travel of the member when so desired.

8. The device of claim 3 in which the member is a diafragma.

9. The device of claim 8 in which the spring means acts to oppose movement of the member by the pressure and to draw fuel into the bore from the port opening.

10. The device of claim 8 in which the plunger is a solid cylinder constantly engaging the member, and the passageway is in a tube opening into the chamber.
